UNITED STATES PATENT OFFICE.

LOUIS CHAMBON, OF PARIS, FRANCE.

COMBINED GUMMING AND CUTTING APPARATUS FOR PAPER, CARTONS, AND THE LIKE.

Application filed April 5, 1923. Serial No. 630,145.

To all whom it may concern:

Be it known that I, LOUIS CHAMBON, citizen of the Republic of France, residing at 64-70 Rue de Crimée, Paris, Seine, France, have invented a Combined Gumming and Cutting Apparatus for Paper, Cartons, and the like, of which the following is a specification.

The invention has for its object a machine for gumming paper or the like which is received in wide spools gummed and cut to spools of suitable width. The machine has the following characteristics.

A gumming element or a number of independent adjustable elements deposits or deposit the gum upon a sheet of paper, the said sheet of paper being wound round a large drum which is heated internally or externally either by electrical resistance or by hot air or gas or any other suitable means for drying the gum. The paper then passes between a series of circular knives or cutters and is rewound on independent drums.

In order that the invention may be fully understood I will describe it by reference to the accompanying drawings in which:

Figure 1 is a front elevation of one form of machine embodying the invention.

Figure 2 is an end view thereof.

Figures 3 and 4 are detail views of the gumming mechanism.

Referring first to figure 1, it will be seen that the machine comprises a drum or spool carrier 1; a driving shaft 3 actuated by a counter shaft 2 driven by a pulley 4, the latter being actuated in any convenient manner; a large drying drum 5 connected through the medium of gear wheels 6, 7, and 8, on the one hand to a rubber cylinder 9 over which passes the sheet of paper to be gummed and on the other hand to a transverse countershaft 10 carrying the pinions 11 designed to operate the groups of gummers 12; a series of groups of gummers 12 corresponding to the number of bands or strips to be gummed and carried by a transverse member 13, these groups being connected by gear wheels 14, to the aforesaid transverse shaft 10; an arrangement of circular knives 15 and 16 upon which rest by means of their own weight independent spools or drums 18 and 19 carried by levers 17 carried by the pivots 29, an arrangement already known and adapted to the present machine

and designed to cut the sheet of paper after 55 gumming and drying and rewinding the spools thus obtained.

The several parts above enumerated are actuated by the shaft 3. This shaft carries three worms 20, 21, and 21¹, designed the 60 one to drive the drying drum 5 by means of the toothed pinions 8 and 6, the other two worms driving the shafts 22, 22', carrying the circular knives or cutters 15 and 16 by the intermediary of the worm-wheels 23 65 and 23'.

The drying drum 5, controlled by the gear-wheels above mentioned, rotates at the same linear speed as the sheet of paper which surrounds it, and by heating arrangements, dries the gum deposited by the groups hereinafter described, before the said sheet reaches the circular knives.

This drum drives, by means of the toothed pinions on the one hand a rubber cylinder 9 75 serving as a table for the application of the gum by the gumming rollers 12' and on the other hand the gummers themselves.

Each of the gumming rollers is carried by a member 24 designed to occupy upon 80 the common transverse member 13 the desired lateral position. This member 24 consists of a fixed part 25 upon which is mounted an adjustable carriage 24 enabling a suitable touch to be given by the gummer 12' 85 of which the lower part is immersed in a cup or receptacle 26 containing the gum.

The rotation of the gumming roller 12' is assured by the pinions 11 and 14 driven by the main gear-wheels 6 mounted upon the 90 drum 5. The regulation of the amount of gum upon the rollers is effected by a hinged scraper 27 which can be adjusted by the screw 28.

The machine as above constructed functions in the following manner:

The sheet of paper rolled around the drum 1 passes firstly into the gumming device where the gumming rollers 12' deposit upon it longitudinal layers of gum. The sheet 100 of paper thus gummed then passes around the drying drum 5 and thence to the circular knives or cutters 15 and 16, functioning like scissor-blades, which cut the sheet longitudinally. This cutting is made at the middle of the line of gum, several millimetres broad, in such a manner that each of the bands thus obtained has its two edges 105

gummed. The gummed bands are then rolled alternately upon the independent drums 18 and 19 placing some in front and some behind and driven by contact with the 5 circular knives 15 and 16.

A machine constructed as above described possesses the advantage of giving a very regular gumming of the extreme edges of the strips or bands which is indispensable in 10 certain cases, as, for example, in the manufacture of gummed cigarette papers, etc.

It will be understood that this machine will equally well serve for gumming sheets or strips over the whole surface by simply 15 replacing the independent rollers 12' by a continuous gumming roller; the arrangement for cutting the sheets into suitable widths being at the same time retained. In this way spools of gummed paper can be 20 obtained such as are required, for example, in the manufacture of postage stamps, gummed labels and the like.

Having now particularly described and ascertained the nature of my said invention 25 and in what manner the same is to be performed I declare that what I claim is:

1. A combined gumming and cutting machine for a paper strip, comprising, in combination, gumming means for applying 30 spaced longitudinal strips of gum on the paper strip, a drying means for the strips of gum, cutting means for cutting the gummed strip longitudinally along the center line of each strip of gum, and means for separately

winding up the thus prepared separate 35 strips of paper.

2. A combined gumming and cutting machine for a paper strip, according to claim 1, said gumming means including, a transverse bar, independent carriages slideable on 40 the bar, a gumming roll in each carriage and adjustable relative thereto, a scraper for each roll, and screw adjusting means for each scraper.

3. A machine for gumming and cutting 45 paper, comprising, in combination, means for applying strips of gum to a piece of paper, means for drying the applied strips of gum and means to simultaneously cut the paper into separate strips and to separately 50 wind up each of said strips.

4. A machine for gumming and cutting paper, comprising, means to simultaneously cut a piece of paper into separate strips and to separately wind up each of the strips, 55 such means including, in combination, a series of circular cutters placed alternately in opposing positions to each other and having their opposing edges slightly overlapping in order to exert a shearing cutting action, two fixed axes, levers pivoted for free rocking movement on the axes, reels mounted on the pivoted arms and bearing against the cutters by their own weight and thereby rotated by the cutters. 60

In testimony whereof I have signed my name to this specification.

LOUIS CHAMBON.
